CLAIM

The ornamental design for a pet waste collector, as shown and described.

DESCRIPTION

FIG. 1 is a top view of a pet waste collector shown in a closed, folded flat configuration in which the detachable scooper element is initially attached to the handle component panel which is attached to the main body of the waste collector;

FIG. 2 is a bottom view of the pet waste collector of FIG. 1; FIG. 3 is a top view of the pet waste collector in an open flat configuration;

FIG. 4 is a bottom view of the pet waste collector shown in FIG. 3;

FIG. 5 is a rear perspective view of the pet waste collector in a first open expanded configuration shown with the scooper being disconnected from the handle;

FIG. 6 is a front perspective view of the pet waste collector shown in FIG. 5;

FIG. 7 is a top view of the pet waste collector shown in FIG. 5;

FIG. 8 is a bottom view of the pet waste collector shown in FIG. 5;

FIG. 9 is a left side view of the pet waste collector shown in FIG. 5;

FIG. 10 is a right side view of the pet waste collector shown in FIG. 5;

FIG. 11 is a perspective view of the pet waste collector in a second open, expanded configuration; and,

FIG. 12 is a perspective view of the pet waste collector in a closed expanded configuration.
